UNITED STATES PATENT OFFICE.

ALBERT A. E. STERZING, OF NEW YORK, N. Y.

TRANSOM-PIVOT.

1,116,511.

Specification of Letters Patent. Patented Nov. 10, 1914.

Application filed July 28, 1905, Serial No. 271,651. Renewed March 25, 1914. Serial No. 827,249.

To all whom it may concern:

Be it known that I, ALBERT A. E. STERZING, a subject of the King of Great Britain, and a resident of the city, county, and State of New York, have invented certain new and useful Improvements in Transom-Pivots, of which the following is a specification.

My invention relates to pivots, and more particularly to pivots such as are used for pivotally mounting objects, especially window sashes and transom or fan lights.

An object of the invention is to provide a pivot which shall be simple and cheap in construction and durable and efficient in operation.

A further object of the invention is to provide a pivot which may be easily and quickly put into operative position and which when in operative position will present a continuous surface adapted to conform with the surface of the adjacent wood-work.

It is also an object of the invention to provide a pivot which shall be proof against the passage of light, air, dust, storms, etc.

These and other objects of the invention will in part be obvious and in part made clear from the following description.

My invention consists in the novel parts, improvements, and features of construction herein shown and described.

The accompanying drawings, which are referred to herein and form a part hereof, illustrate one embodiment of the invention together with a certain modification thereof, the same serving in connection with the description herein to explain the principles thereof.

Of the drawings, Figure 1 is a face view of one member of a pivot constructed in accordance with the invention; Fig. 2 is a similar view of the other member; Figs. 3 and 4 are similar views illustrating a modification; Fig. 5 is a side elevation of same with the parts assembled; Fig. 6 is a vertical central sectional view of the same; Fig. 7 is a side elevation of a transom door frame and a fan light mounted therein with the form of the device illustrated in Figs. 1 and 2, the parts at one side being in vertical section to more clearly illustrate the construction; Fig. 8 is a vertical section on the line 8—8 of Fig. 7, the parts being shown in a different position; Fig. 9 is a similar view with the fan light and pivot

removed; and Fig. 10 is an end view of the fan light and the pivot member thereon.

A pivot made in accordance with my invention comprises a pair of pivot members having oblong body portions terminating in complementary wings or extensions, the said body portions having means adapted to form a pivotal connection between the members and also having provision for securing the members in position. In accordance with one feature of the invention, the opposite edges of the pivot members are formed on parallel lines, and one edge of each of the wings forms an extension of the corresponding edge of the body portion. In accordance with another feature of the invention, each of said wings has a thickness corresponding to the combined thicknesses of the two body portions of the pivot, whereby when the members are assembled and in their closed relation a structure is provided, the opposite longitudinal edges of which present practically continuous parallel surfaces. In accordance with one feature of the invention, the body portions are provided with one or more projections and recesses concentrically arranged with relation to the pivotal axis of the members, the same serving to span the space between the thickened wings or extensions so as to seal the joint between the two members, thereby preventing the passage of light, air, dust, rain, etc., through the same. In accordance with another feature of the invention, the body portions as well as the extensions thereof serve as a means for securing the members in place. These and other features of the invention will be more particularly set forth in the following description.

Referring in detail to the particular embodiments of the invention illustrated in the drawings, and first to the form of the device shown in Figs. 1 and 2, A, B represent the body portions of the two members of the device. As shown, the opposite edges of each of these body portions are formed in straight parallel lines. Suitable pivotal connection between the members is provided, the same consisting, in the particular embodiment of the invention illustrated, of the stud 5 of the member B which turns in the corresponding aperture 6 of the member A, and which stud may be of any desired length to provide against shrinkage of the wood in which the pivot members may be placed.

Complementary wings 7, 8, and 9, 10 extend from the members A and B, respectively, one edge of each wing preferably forming an extension of the corresponding edge of the body portion from which said wing or extension projects. Each of the wings or extensions 7, 8, 9, and 10 is preferably made of a thickness substantially equal to the combined thicknesses of the body portions 5 of the members A and B, so that when the members are assembled and in their closed relation, the opposite longitudinal edges of the structure thereby formed will present practically continuous parallel surfaces, as indicated in dotted lines in Fig. 1.

An important feature of the invention consists in the provision of means for spanning the space between the wings or extensions when the members are in their closed 10 relation so as to seal the joint between the two members. As shown in Figs. 1 and 2, this is done by providing the circular recess 14 of the member A, which is arranged 20 concentrically with relation to the stud 5 and in which recess loosely fits the projection 15 of the member B.

When the device is used with a door frame and fan light, for instance, it may be desirable that the fan light shall be allowed to 30 open to its fullest extent, as shown in Fig. 8. In this case the moving member of the pivot will be in a position at right angles to the stationary member. To permit of such movement, the longitudinal distance between the innermost extremities of the 35 wings or thickened extensions of each of the members must be at least equal to the width of the body portion of its co-operating member; and to effectively span this space, the 40 circular recess 14 of the member A and its corresponding projection 15 of the member B shall each have a diameter greater than the width of the members. It will be noted that in this case the center part of the pivot 45 will not be properly sealed by the recess 14 and projection 15, as the opening formed by the intersection of the recess with the opposite edges of the body portion of the member A may be somewhat greater than the 50 width of the pivot 5. In order to span these central openings, a second smaller concentric circular recess 16 and projection 17 may be provided, the recess preferably being formed on the member A and the projection 55 on the member B, as shown.

An important feature of the invention is the great strength of the pivot members A and B, and this is furnished by giving the body portion of each member a longitudinal 60 extent which is materially greater than its width and by connecting the wings or extensions to the body portions on oblique lines so as to afford elongated lines of connection between the extensions and the body 65 portion as well as to permit the proper

opening and closing or pivotal movements of the members with relation to each other. Preferably, the body portion is so extended that it may serve as a means for securing the members in place in addition to the 70 wings, thereby relieving the strain on the connection between the wings and the body portion.

Any suitable means may be employed for securing the members in place. As shown, 75 holes are provided for the reception of screws, said holes being preferably so disposed as not to diminish the strength of the members. They may be arranged within the circular recesses or projections, as shown, 80 for example, in Fig. 1, or they may be arranged upon the circular recesses or projections as indicated in Fig. 2. Preferably, also, each of the wings is provided with securing means, as for instance, the hole for 85 the reception of the screw.

An important feature of the invention is found in the shape of one of the wings or extensions whereby the setting of the pivot is facilitated. In accordance with this feature, one of the wings, and preferably one of the wings of that member which is to be relatively fixed, is extended or so formed that when the member has been fitted in place in the door or window frame, the 90 weight of the sash or fan light to which the other member is secured will tend to hold the pivot in its fitted position. As shown, the upper wing or extension 9 of the member B is extended upwardly along 100 its inner vertical edge so as to provide a downwardly and outwardly inclined upper end. By reason of this construction the pivot with one of its members attached to the sash or fan light and the other member 105 loosely engaged therewith may be slipped in place in the recess provided for the relatively fixed member in the door frame and removed, as required, for proper fitting with ease and without liability of the unattached 110 sash or fan light dropping out. In the case of a fan light, for instance, at each end of the light a pivot member may be secured in position, as indicated at A in Fig. 10, suitable beads 18 and 19, preferably of the 115 same width and thickness as the wings of the pivot member, being secured in line with said wings. The proper places for the other members B of the pivots being marked upon the door frame, as nearly as may be, beads 120 21 and 22 are secured in place temporarily or otherwise, as shown in Fig. 9, the upper bead members 21 being shaped at their lower ends to correspond to the inclined ends of the upper wings or extensions of the pivot 125 members B. The pivot members B may then be slipped in place upon the members A and the fan light placed in position in the door frame. As the pivotal connections between the members come in line with the 130

inner edge of the lower beads 22, the weight of the fan light will tend to cause it to fall out of its place. The upper tapering edges of the ends of the wings or extensions of the members B will prevent this, however, by contact with the correspondingly shaped ends of the beads 21. After any alterations have been noted, the parts may be removed and the alterations made; and if desired, 10 the fitting operation may be repeated without danger of the fan light falling out of place when temporarily inserted. After the fitting is completed, the members B may be secured in place by turning the fan light 15 into the horizontal position, as indicated in Fig. 8.

The embodiment of the invention illustrated in Figs. 3, 4, 5, and 6 shows a modification which is particularly suitable for use 20 with transom windows or fan lights. It is not always desirable that a fan light should be capable of being opened to the fullest extent so that the window shall be in a position at right angles to the casing or frame 25 but rather is it suitable that the window should open to a more limited extent. In such a case the longitudinal distance between the innermost extremities of the thickened wings or extensions 7', 8', and 30 9', 10' may be somewhat less than the width of the body portions of the members, in which case the diameter of the circular recess 16' of one member and the diameter of its corresponding projection 17' may each 35 be less than the width of the members without permitting the passage of light, air, dust, storms, etc., through the pivot, a second recess or projection being therefore unnecessary.

40 It will be understood that where it is not desired to make special provision for sealing the pivot against the passage of light, air, etc., the projections and recesses may be omitted.

45 It will be seen that by reason of the construction shown and described a pivot which is of maximum strength at all points is provided and at the same time the construction is simple and neat in appearance and easily 50 applied. In accordance with the preferred construction also, a pivot is provided which is perfectly sealed from the passage of air or dust, etc.

55 A special advantage of the construction resides in the fact that when in the closed position, it presents at its visible edges a surface which is smooth and continuous and forms or may form a practical continuation of the woodwork in which it is fitted, and 60 particularly of the beads which are commonly used in fitting pivot window sashes and fan lights, the opposite edges of the members being rounded, as indicated in the drawings, to correspond with the rounded 65 edges of the beads or moldings. Another

advantage of my invention is that it provides a simple construction of such a character that it may be formed of simple castings which require little or no fitting.

It is to be understood that my invention 70 in its broader aspects is not limited to the precise construction shown nor to any particular construction by which the invention has been or may be carried into effect, as many changes may be made in the details 75 of the parts without departing from the main principles of the invention and without sacrificing its chief advantages.

What I claim is:

1. A pivot consisting of a pair of pivot 80 members having oblong body portions the opposite edges of which are formed on parallel lines, said members having means adapted to form a pivotal connection between them, and said members being provided with complementary wings or extensions, one edge of each wing forming a continuation of one of the parallel edges of its body portion, whereby when the members are assembled in their closed relation, the 85 opposite longitudinal edges of the pivot present practically continuous parallel surfaces adapted to conform with the adjacent surfaces of the structure to which the pivot may be attached. 90

2. A pivot consisting of a pair of pivot members having oblong body portions the opposite edges of which are formed on parallel lines, said body portions having means adapted to form a pivotal connection between the members, and said members having oppositely arranged complementary wings or extensions, the edge of each wing forming an extension of one of the parallel edges of its body portion, and each of said 100 wings having a thickness substantially equal to the combined thicknesses of the two body portions of the pivot, whereby when the members are assembled in their closed relation, a structure is provided, the opposite 105 longitudinal edges of which present practically continuous parallel surfaces. 110

3. A pivot consisting of a pair of pivot members having oblong body portions the opposite edges of which are formed on parallel lines, one said body portion having a perforation and the other an integral projection fitted to said perforation to form a pivotal connection between the members and both having countersunk perforations adapted to receive screws, and said members having oppositely arranged complementary wings or extensions, the edges of each wing forming an extension of one of the parallel edges of the body portion, and each of said 115 wings being parallel with a countersunk perforation adapted to receive an attaching screw and having a thickness substantially equal to the combined thicknesses of the two body portions of the pivot, and said body 120 125 130

portions being provided with a projection and recess concentrically arranged with relation to the said pivotal connection and spanning the space between the thickened wings
5 or extensions so as to seal the joint between the two members.

In testimony whereof, I have signed my

name to this specification, in the presence of two subscribing witnesses.

ALBERT A. E. STERZING.
